UNITED STATES PATENT OFFICE.

MORRIS H. LIPMAN, OF NEW YORK, N. Y.

DESIGN FOR A HOOK FOR SHOE-LACES.

SPECIFICATION forming part of Design No. 30,301, dated February 28, 1899.

Application filed January 14, 1899. Serial No. 702,187. Term of patent 14 years.

To all whom it may concern:

Be it known that I, MORRIS H. LIPMAN, of the city of New York, borough of Manhattan, in the county and State of New York, have invented and produced a new and original Design for a Hook for Shoe-Laces, of which the following is a specification, reference being had to the accompanying drawings, forming a part thereof, in which—

Figure 1 is a perspective view of a hook embodying my design, the view being taken from the top; and Fig. 2 is a similar view of the hook, the view being taken from the bottom.

The design consists in a loop-shank A, a single body-shank B, appearing continuous with the loop-shank and of greater width, and a return member C, that extends over but out

of engagement with a face of the single shank in direction of the loop-shank. A depression D is apparently in the single shank opposite its return member.

The leading feature of the design consists in the loop-shank and single shank appearing continuous with the loop-shank, the single shank having the member returned in direction of the loop-shank.

I claim—

The design for the hook for shoe-laces, herein shown and described.

MORRIS H. LIPMAN.
